US0D1087032S

(12) **United States Design Patent** (10) **Patent No.:** **US D1,087,032 S**
(45) **Date of Patent:** **** Aug. 5, 2025**

- (54) **MEDICAL DEVICE CONNECTOR**
(71) Applicant: **Physio-Control, Inc.**, Redmond, WA (US)
(72) Inventors: **Christopher Alviar**, Seattle, WA (US); **Ryan Bowman**, Richland, WA (US); **Neal Clark**, Snohomish, WA (US); **Zack Pahlman**, Redmond, WA (US); **Jeremy Wong**, Redmond, WA (US); **John Depillo**, Redmond, WA (US)
(73) Assignee: **Physio-Control, Inc.**, Redmond, WA (US)
(**) Term: **15 Years**
(21) Appl. No.: **29/913,999**
(22) Filed: **Oct. 11, 2023**
Related U.S. Application Data
(63) Continuation of application No. 29/808,242, filed on Sep. 17, 2021, now Pat. No. Des. 1,007,438, which is a continuation of application No. 29/708,182, filed on Oct. 3, 2019, now Pat. No. Des. 933,612.
(51) **LOC (15) Cl.** **13-03**
(52) **U.S. Cl.** **USPC** **D13/147; D24/107**

(57) **CLAIM**

The ornamental design for a medical device connector, as shown and described.

DESCRIPTION

FIG. 1 is a top perspective view of a medical device connector;

FIG. 2 is an enlarged view of a left perspective of the medical device connector shown in FIG. 1;

FIG. 3 is a top view thereof;

FIG. 4 is a front side view thereof;

FIG. 5 is a back view thereof; and,

FIG. 6 is a side view thereof.

The broken lines in the drawings illustrate portions of the medical device connector that form no part of the claimed design.

1 Claim, 4 Drawing Sheets
